UNITED STATES PATENT OFFICE.

PHILO WILLIAM CASLER, OF LITTLE FALLS, NEW YORK.

DESIGN FOR A BOOKCASE.

SPECIFICATION forming part of Design No. 34,583, dated May 28, 1901.

Application filed February 28, 1901. Serial No. 49,361. Term of patent 7 years.

To all whom it may concern:

Be it known that I, PHILO WILLIAM CASLER, a citizen of the United States, residing at Little Falls, in the county of Herkimer and State of New York, have invented a new and original Design for Bookcases; and I do hereby declare the following to be a full, clear, and exact description of the invention, such as will enable others skilled in the art to which it appertains to make and use the same.

My invention relates to a new and original design for bookcases, and has for its object to provide a bookcase that shall be ornamental and attractive.

In the drawing, A is the lower portion, and B the upper portion, of the bookcase. C represents the sides or the ends of the said portions and which are provided with vertical panels D. The sides are further provided

with molded front edges E. F represents the projecting portions of the sides of the said upper portion of the case, and which is curved as to form a continuous front edge F' for the said upper and lower portion.

G represents a cornice attached to the upper portion, and H represents a base-molding for the lower portion.

Having thus described my newly-invented design, what I claim, and desire to secure by Letters Patent, is—

The design for a bookcase substantially as shown and described.

In testimony whereof I affix my signature in presence of two witnesses.

PHILO WILLIAM CASLER.
